UNITED STATES PATENT OFFICE.

WINFIELD W. CONARD, OF NORRISTOWN, PENNSYLVANIA.

APPARATUS FOR BURNING PULVERIZED FUEL.

1,370,091.

Specification of Letters Patent.

Patented Mar. 1, 1921.

Application filed July 15, 1916. Serial No. 109,477.

To all whom it may concern:

Be it known that I, WINFIELD W. CONARD, a citizen of the United States, residing at Norristown, in the county of Montgomery and State of Pennsylvania, have invented 5 certain new and useful Improvements in Apparatus for Burning Pulverized Fuel, of which the following is a specification.

This invention relates, broadly stated, to 10 apparatus for burning pulverized fuel, such as powdered coal, slack, culm, lignite or any other like combustible matter, in a furnace for the purpose of heating buildings, driving machinery, propelling vehicles, locomotives, 15 boats or vessels, developing power, or for any other purpose for which a furnace may be used, and the invention has more particular relation to the providing of such apparatus for use upon an automobile.

20 The principal object of the present invention resides in the providing of apparatus for burning pulverized fuel in which the construction is such that the fuel may be economically burned and in which various 25 coöperating parts are employed for effectively practising the invention in a commercially valuable manner.

Other and further objects of the invention 30 will be apparent from the detailed description following.

The invention consists of the improvements hereinafter described and finally claimed.

35 The nature, characteristic features and scope of the invention will be more fully understood from the following description taken in connection with the accompanying drawings forming part hereof and in which:

40 Figure 1 is a top or plan view, somewhat diagrammatic in character, of an automobile chassis equipped with apparatus embodying the invention.

45 Fig. 2, is an elevational view, principally in section, of the forward end of the automobile.

Fig. 3 is a top or plan view of Fig. 2.

Fig. 4, is a similar view illustrating a conveyer and pulverizer hereinafter referred to.

50 Fig. 5, is a fragmentary view in section of the spherical member shown in Fig. 4.

55 Fig. 6, is a top or plan view showing more or less diagrammatically a modified form of apparatus embodying features of the invention, and

Figs. 7 and 8 are fragmentary views illus-

trating details of construction of certain of the parts shown in Fig. 1.

For the purpose of illustrating my invention, I have shown in the accompanying 60 drawings one form thereof which is at present preferred by me, since the same has been found in practice to give satisfactory and reliable results, although it is to be understood that the various instrumentalities of 65 which my invention consists can be variously arranged and organized and that my invention is not limited to the precise arrangement and organization of the instrumentalities as herein shown and described.

70 In order to illustrate the principle of the invention a construction suitable for automobile use has been shown in the drawings and the following description is therefore restricted to such showing. In the specific 75 instance shown in the drawings the chassis of the car is designated 10 and may be of any suitable design. Suitably mounted at the front thereof is a combustion chamber 11 constructed of fire brick or other refractory material at one end of which is an opening 12 through which currents of air are introduced. The currents of air carry in suspension particles of pulverized fuel that are introduced into the currents of air from 80 a receptacle 13 of suitable air tight construction by means of a conveyer 13' operative within a nozzle 14. This nozzle 14 may be internally provided with spiral vanes 50 to impart a whirling motion to the fuel as fed 85 through said nozzle. One current of air may be produced by a fan 15 or other device for producing a forced draft which fan 15 is located adjacent to the above mentioned conveyer and nozzle. In addition to the 90 above mentioned current of air which may be termed a primary air blast; I employ another current of air which is also introduced through opening 12. This latter current of air may be termed a secondary air 95 blast and is produced by a fan 17 shown in front of the combustion chamber 11. In order to shorten the time required for combustion and hence keep the volume of the combustion chamber down to a size that may 100 be readily accommodated in a limited space, such as in an automobile chassis, I find it is desirable to heat the air supporting combustion. By thus heating the air I can increase the efficiency of the apparatus. As 105 shown such secondary air current is drawn through the radiator 18 that condenses ex-

haust steam where it is partially heated and then passes between the flue tubes 19 that carry away from the furnace and boiler 20 the burnt gases resulting from combustion.

5 The secondary air current travels in a reverse direction to that of the passage of burnt gases of combustion so that it becomes hotter as it advances toward opening 12. These flue tubes in practice are so arranged

10 and constructed as to most efficiently radiate the heat. After this secondary current of air passes over the boiler 20, it descends through two large spouts 21—22 one on each side of the boiler which spouts converge at

15 the opening 12 in close proximity to the primary air blast. In some instances, a branch 21' from the above spouts may if desired lead to the fan 15 so as to give hot air for the primary air blast. This latter provision

20 may or may not be desirable according to the kind of fuel used. 23 designates a tank for containing petroleum, kerosene, gasolene, alcohol or any other inflammable liquid or gas. A valved pipe 24 leads from said tank

25 to an air pipe 25 which in turn leads to an oil burner 26 from a source of compressed air contained for instance in tanks 27. The burner 26 may be ignited by means of a pilot flame, match, torch, or electric spark at

30 which time a valve 28 is opened in the pipe leading from liquid fuel tank to the igniter. At the same time a valve 29 is opened in the pipe that leads from one of the air tanks to an admission end of air engine 30. This air

35 engine operates fans 15—17—31. The exhaust from the air engine 30 still at a certain desired pressure above the atmosphere goes to the oil burner and carries into the combustion chamber over the igniter the

40 liquid fuel in the form of a fine spray which is ignited, the air engine actuating the fans creating a draft of air necessary for complete combustion of the liquid fuel. By this means sufficient heat is developed to quickly

45 raise steam. When steam is raised, controls operated by either hand levers or foot pedals, shift gear wheels 59 and 61, open three-way valve 37 in said pipe 25 so as to make connection between the air engine 30 and the

50 atmospheric air; open throttle valve 32 in steam pipe 64 between the boiler and engine, and throw in clutch 33. Gear wheels 59 and 61 are secured to and rotate in unison with a sleeve 63 and by means of the above mentioned control, when steam is raised, are shifted so that gear wheel 59 is thrown into mesh with gear wheel 60 and simultaneously gear wheel 61 is thrown out of mesh with gear wheel 62. Thus the steam engine

55 through the belt or endless chain 35, train of gear wheels A and complementary shafts and pulleys operate the fans 15, 17, 31 and also as hereinafter described, the pulverizer, mechanical conveyer and (through the

60 clutch 33) air engine 30, in a reverse direc-

tion. The air engine 30 now operates as an air pump for drawing air from the atmosphere in through valve 37 and pumping it into tanks 27 to replenish air pressure therein so that the same may be ready for initial

65 starting of the apparatus or for filling tires with air when desired. 51 designates a cylinder of an automatic cut off which cylinder has a moving piston therein the piston-rod of which is connected to a link 52 which

70 link in turn is connected to one end of the pivoted arm 53. The opposite end of arm 53 is attached to a collar 54 carrying the clutch fingers of clutch 33. A spiral spring 55 is attached to one side of this collar and

75 bears against the hub of beveled gear wheel 56. A stop-cock 57 may be operated to prevent air leakage when the apparatus is not in use. The above described automatic cut off operates in the following manner: When

80 the steam engine is in operation and air pressure in the tank is below normal, the spring 55 holds the collar 54 up so that the clutch fingers close the clutch 33 and at the same time, through pivoted arms 53 and

85 links 52, the piston in cylinder 51 is held tight up against the opening leading from stop cock 57 to said cylinder. The clutch being closed, the steam engine, as above described, operates fans, pulverizer and me-
chanical conveyer and reverses the movement of the air engine so that the latter becomes an air pump. As soon as the air pressure rises to the safety point in the tanks 27, the piston in cylinder 51 overcomes the resist-
ance of spring 55 so that clutch 33 is opened, thus stopping any further rise in pressure in the air tanks. An independent means of opening the clutch 33 is provided by the pro-
longation of lever 53 extending to the left
of the link 52 so that said lever may be operated by manual control and the clutch 33 opened by hand just prior to the opening of valve 29, when the air engine is first started so as to avoid causing the air engine to
operate the steam engine in a reverse direc-
tion, or it may be closed by hand when the operation of the steam engine is started as described above. The air engine 30 drives fans 15, 17 and 31, and by means of cogs
and bevel gears and shafts, chains or any of the other well known means of transmitting power. I also have in mind as part of the present invention to drive the fans by electric motor 65 fed by current from a storage

100 battery 66 that is kept charged by an electric generator 67. The latter is mounted upon the main engine shaft or may be connected by gear or shafts with said main engine shaft. The electric generator storage

105 battery and motor take the place of the air engine 30 and air tanks 27. With this present arrangement when it is desired to get up steam the valve 28 is opened and the liquid fuel is permitted to pass to the

110

115

120

125

130

burner 26. The switch for starting the motor is operated and the motor through gear wheels 61 and 62 operates the fans 15, 17, and 31. A branch air conduit pipe 5 68 is employed in connection with fan 15 and a deflecting gate 69, pivoted to a hinge as at 70, causes drafts of air to pass through the said branch conduit to the oil burner 26. The liquid fuel is there ignited and blown 10 in the form of a spray into the combustion chamber thus causing a great heat whereupon steam may be quickly raised. Steam being raised the throttle 32 is opened, the starter switch controlling the motor is opened and the motor stops. The deflecting gate 69 is turned so as to permit drafts of air from fan 15 to pass through nozzle 14 and collar with gear wheels 59 and 61 attached thereto are shifted so as to cause gear 15 wheel 59 to mesh with gear wheels 60 and so 20 as to cause gear wheel 60 to be out of mesh with gear wheel 62. The steam engine will then through belt or chain 35 and the gear wheels A, drive the fans 15, 17 and 31, conveyor for the pulverized coal and the pulverizer. When the steam engine is in operation the electric generator 67 generates electric current to re-charge the battery 66 for use in re-starting. I also have in mind 30 as part of this invention the driving of the fans, mechanical fuel conveyor and pulverizer either partly or entirely by means of shafts, chains or cogs from the main engine or moving wheels or axles.

35 A description will now be given of the pulverizer. This device is for pulverizing the fuel in the receptacle 13 to the proper degree of fineness for quick and complete combustion in the above described furnace. 40 This device is located in the bottom of the fuel receptacle 13 which latter is tapered so that the fuel will naturally gravitate toward it. I have illustrated in the drawings a form of pulverizer consisting of a 45 spherical metallic member 36 provided with tangentially formed ridges 37 upon its lower surface. The ridges may decrease in height from the base circumference toward the center thereof. The spherical member 36 is held against the bottom of receptacle 13 by a coiled spring 38 surrounding shaft 39 which is connected to gear wheel 40. The wheel 40 is operated by the main engine through suitable connections as described 50 above. I do not wish to be limited to the use of the above described pulverizer as any pulverizer that will reduce the fuel to the desired degree of fineness may be employed. Leading from that part of the receptacle 13 beneath the pulverizer is a spout 55 41 for conveying material as pulverized to the conveyor 13'. The above mentioned pulverizer may be omitted under certain conditions, for example in trucks, tractors or engines or furnaces that are in continu-

ous or substantially continuous use, where fuel pulverized to a fineness sufficient to burn properly may be placed directly in the fuel receptacle. The advantage of the pulverizer is where the use of a furnace, engine, 70 vehicle or other apparatus is so intermittent that there is danger of the fuel taking fire spontaneously through exposure to the air for too long a period of time. By means of the pulverizer, fuel may be placed 75 in the fuel receptacle 13 in a dry state and as fine as possible without danger of spontaneous combustion, then pulverized as needed. With the introduction of the pulverized fuel to the conveyor 13' it is brought 80 forward by conveyor 13' to the entrance 12 of the furnace at which point it is mixed with both currents of air previously described so that there is thus insured a quick and complete combustion. At the forward end of 85 combustion chamber there is a depression 43 for the collection of slag, cinders and ashes. The bottom of this is removable in any desired manner so that the slag, cinders and ashes may be removed. A perforate 90 arch 44 of brick or other refractory material forms the top of the combustion chamber, the object being to insure complete combustion before the fuel, gas or air enters the boiler tubes 71, these boiler 95 tubes are connected at the boiler top with flue tubes 19 which tubes may discharge in any direction. In locomotives, boats, vessels, stationary power plants or heating furnaces, they may discharge upward into a 100 stack. For automobiles, trucks or tractors, they discharge either downward as shown or through a stack or pipe leading to rear of vehicle. The tubes, as shown, converge at the outlet ends and a fan 31 is present, 105 operative as above described, for drawing products of combustion within the tubes to the atmosphere. The conduit for the secondary air current may be lined with asbestos or magnesia covering 45 to 110 conserve the heat of the secondary air current and prevent loss of heat through radiation. The boiler may be equipped with any well known form of safety valve, pressure gage, superheater, feed water heater, automatic water level indicator, fuel cut-off, 115 pumps and manual controls. Also usual steam pipes with throttle control to main engine may be employed.

120 From the foregoing detailed specification, it is thought that the operation of the apparatus will be readily understood without resorting to further description thereof.

It will now be apparent that I have devised a novel and useful construction which 15 embodies the features of advantage enumerated as desirable in the statement of the invention and the above description and while I have in the present instance shown and described the preferred embodiment 130

thereof which has been found in practice to give satisfactory and reliable results, it is to be understood that the same is susceptible of modification in various particulars without departing from the spirit or scope of the invention or sacrificing any of its advantages.

What I claim is:

1. Apparatus of the character stated comprising the combination of a boiler including its combustion chamber, means for feeding pulverized fuel to said combustion chamber, a liquid fuel device located within the combustion chamber for initially heating the boiler, an air engine and means connecting the exhaust of said engine with the liquid fuel device for effecting a spray of the liquid fuel. 70
2. Apparatus of the character stated comprising the combination of a boiler including its combustion chamber, means for feeding pulverized fuel to said combustion chamber, a liquid fuel device located within the combustion chamber for initially heating the boiler, means for creating a draft through the boiler, means for passing a primary and secondary blast of air to said combustion chamber, an air engine, means connecting the exhaust of said air engine with said liquid fuel device and means connected with said air engine for operating the draft and air blast producing means. 80
3. Apparatus of the character stated embracing a boiler and its complemental combustion chamber, means within said chamber for initially heating the boiler, mechanism for conveying pulverized material to the combustion chamber subsequent to the initial heating period, means for commingling with said material a primary and secondary air blast of which the primary blast of air is forced directly to the fuel and caused to commingle therewith and of which the secondary blast of air is first heated by the products of combustion from said chamber and then caused to commingle with the previously mixed fuel and primary air blast, means for operating the air blast means during the initial heating period and independent means for operating the air blast means during the feeding of pulverized material. 90
4. Apparatus of the character stated embracing a boiler and its complemental combustion chamber, means within said chamber for initially heating the boiler, a source of fuel supply, means for pulverizing said fuel, means for conveying the pulverized fuel to the combustion chamber subsequent to the initial heating period, means for commingling with said material a primary and secondary air blast of which the primary blast of air is forced directly to the fuel and caused to commingle therewith and of which the secondary blast of air is first heated by the products of combustion from said chamber and then caused to commingle with the previously mixed fuel and primary air blast, a medium for operating said air blast means during an initial heating period and independent means for operating the air blast means and the pulverizer during the feeding of pulverized material. 75
5. Apparatus of the character stated embracing a steam boiler including a furnace, means for conveying pulverized fuel into the furnace thereof, mechanism for supplying a primary and secondary air blast to the material as fed to the furnace of which the primary blast of air is forced directly to the fuel and caused to commingle therewith and of which the secondary blast of air is first heated by the products of combustion from said chamber and then caused to commingle with the previously mixed fuel and primary air blast, means operated by compressed air for creating said air blast for a predetermined period, independent means operated by steam from the boiler for creating said air blast and driving the conveying medium the balance of the time and mechanism for controlling the operations of the air and steam connections. 85
6. Apparatus of the character stated embracing a steam boiler including a furnace, means for conveying pulverized material into the furnace thereof, air blast supplying mechanism for commingling same with said material, a source of compressed air, an air engine connected therewith for operating the air blast mechanism, steam actuated mechanism connected with the conveying means and mechanism for connecting the steam actuated mechanism with the air engine to reverse its action to that of a pump and simultaneously operate the air blast mechanism and conveying means. 95
7. Apparatus of the character stated embracing a steam boiler including a furnace, a source of fuel supply, means for pulverizing said fuel, means for conveying the pulverized fuel to the boiler furnace, air blast supplying mechanism for commingling same with said fuel, a source of compressed air, an air engine connected therewith for operating the air blast mechanism, steam actuated mechanism connected with said pulverizing and conveying means and mechanism for connecting the steam actuated mechanism with the air engine to reverse its action to that of a pump and simultaneously operate the air blast mechanism, pulverizing and conveying means. 100
8. Apparatus of the character stated embracing a steam boiler including a furnace, a source of pulverized fuel supply, means for conveying said fuel to the boiler furnace, mechanism for commingling directly with the fuel a primary blast of air, an air 110
- 120
- 125
- 130

engine for operating said mechanism, a source of air supply for operating the engine, steam actuated mechanism means for connecting the air engine with the steam actuated mechanism to reverse the action of the engine for recharging the source of air supply and independent means for supplying a secondary previously heated air blast.

to the fuel as mixed with the primary air blast.

In testimony whereof I have hereunto signed my name.

WINFIELD W. CONARD.
